DESIGN FOR A FIRE-PLACE.

Design No. 13,446, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,446, dated November 21, 1882.

Application filed October 17, 1882. Term of patent 7 years.

To all whom it may concern:

Be it known that I, WILLIAM C. PEET, of Jersey City, in the State of New Jersey, have invented a certain new and ornamental Design for Fire-Places, of which the following is a specification.

This design is unique, and is principally composed of light tracery in an otherwise flat surface.

- 10 In the annexed engraving my design is shown. The fire-place frame is ornamented with tracery composed of the leaflet and stem ornaments *a*, fan-shaped ornaments *b*, circular ornaments *c d e f*, corner-rosettes *g*, and central concentric circles *h*. The fender-frame is ornamented with the fan-shaped tracery *b*, circular ornaments *h*, and stems, as shown. The andirons have trident ornaments *l* at their upper ends, prismatic stems *m*, conical ornaments *n*, ro-

settes *s*, triangular base with rosette and leaf *t*, as represented. The tracery of the fender and fire-place frame is very similar, and the andirons are designed to form a pleasing contrast to the rest of the parts.

I claim as my invention—

- 25 1. The design of the tracery on the fire-place frame and fender, substantially as represented. 2. The design of the andirons, consisting of the ornamental trident, conical and rosette ornaments, triangular base, and rosette and leaf *30* ornaments, substantially as represented.

Signed by me this 13th day of October, A. D. 1882.

WILLIAM C. PEET.

Witnesses:

WILLIAM G. MOTT,
GEO. T. PINCKNEY.
